UNITED STATES PATENT OFFICE.

MAX SCHEUER, OF NEW YORK, N. Y.

DESIGN FOR A PURSE.

SPECIFICATION forming part of Design No. 35,353, dated December 3, 1901.

Application filed October 18, 1901. Serial No. 79,172. Term of patent 7 years.

To all whom it may concern:

Be it known that I, MAX SCHEUER, a citizen of the United States, and a resident of New York city, county and State of New York, 5 have invented a new and original Design for a Purse, of which the following is a specification, reference being had to the accompanying drawing, forming part thereof, and which represents a front view of my newly-designed 10 purse.

As shown in the drawing, the leading feature of the design consists of the representation of a bust a within an oval frame b. Across and at the sides of the frame are arranged bands c, between which scrolls d are 15 represented. Above the frame are shown flags e, gathered by strings f, the whole being inclosed by a border g.

What I claim is—

The design for a purse, substantially as 20 herein shown and described.

Signed by me at New York city, county and State of New York, this 17th day of October, 1901.

MAX SCHEUER.
